UNITED STATES PATENT OFFICE

JOHN L. McMILLAN, OF SYRACUSE, NEW YORK, ASSIGNOR TO McMILLAN BOOK COMPANY, OF SYRACUSE, NEW YORK, A CORPORATION OF NEW YORK

LOOSE LEAF BINDER

Application filed December 24, 1925, Serial No. 77,564. Renewed December 7, 1929.

My invention relates to what may for brevity be termed loose leaf binders of the link-and-pintle type, and it consists in a lock of novel form and construction, capable of insertion into, and removal with the aid of a key, from the housing of the pintle slide when said slide is in holding engagement with the paper-carrying links, to prevent or permit, as required, longitudinal movement of the slide for the purpose of locking or freeing the slide and the links held thereby.

The construction is illustrated in the accompanying drawings, in which:

Figure 1 is a perspective view on a quite small scale of a binder embodying my invention;

Fig. 2 is a fragmentary elevation of a housing, pintle slide, leaf-carrying link, and lock of said binder, made on a quite large scale, with portions broken away and some parts in section;

Fig. 3 is a transverse sectional view of the same on the line A—A, Fig. 2, passing through the lock, and looking in the direction of the arrows associated with said line;

Fig. 4 is a similar section on the line B—B of Fig. 2, looking in the direction indicated by arrows thereon;

Fig. 5 is a perspective view of the lock-receiving end of a housing, showing the lock withdrawn and at a short distance therefrom.

Binders of the class referred to are extensively used in banks, accounting offices, and like places, to form, with their appropriately ruled leaves, loose leaf ledgers or record books. These books may be made up complete or built up by progressive additions of leaves or sheets on which are made appropriate entries, commonly by typewriting, though they may be made in any convenient way. Minute and record books of corporations, clubs, and various organizations, are likewise equipped with loose leaf binders of this general character, and for like reasons.

It is desirable in these and other cases that the leaves shall be capable of ready insertion, removal, and replacement, in order that the necessary printing or writing may be conveniently done, but it is highly important

that, when the leaves are in place, the leaf-holding devices shall be so securely locked that it will be impossible to insert, remove, transpose, or otherwise disarrange the leaves, or tamper with the records in a manner to avoid prompt detection.

With these objects in view the binder is composed of a back member 1, preferably of curved form in cross section, to opposite longitudinal edges of which are attached by any suitable form or type of hinges, two cover-boards 2 and 3, and at or close to the inner edge of each cover-board there is firmly secured in any convenient or usual way, such for instance, as riveting, a metallic housing 4 within which is arranged a metallic pintle-bearing slide 5, the pintles 6 of which pass through eyes 7 in the ends of leaf-receiving links 8, which bridge or span the back member and serve also to hold the same against spreading or deformation. The pintles serve not only to retain the links 8 in place, but also as hinge pins about which the links may be swung into and out of their normal back-bridging position, to permit and facilitate application, removal, transposition, or substitution of leaves, and subsequent re-engagement by the pintles 6.

The preferred form and construction of the housing is illustrated in Figs. 2 to 5 inclusive. It is conveniently produced by folding a flat sheet metal blank along a line approximately midway between its longitudinal edges and parallel therewith, in an easy curve, to produce a substantially cylindrical back 9, the free edges of the blank being brought into alinement, and the portions of the blank between the rounded back 9 and said free edges being placed parallel with each other and spaced apart a distance sufficient to receive between them the inner edge portion of one of the cover-boards 2 or 3. To stiffen the housing and prevent bending or buckling thereof, to form a stop for the edge of the cover-board, and to produce a guide for the edge of the pintle-slide 5, there is formed in one leaf of the folded blank a rectangular or trough-like bend or corrugation 10, parallel with the longitudinal edges of the blank, and of a depth to rest upon the other leaf of

the blank and act as a spacing member to hold the two leaves of the housing at the desired distance apart.

To afford adequate and suitable space for a lock 11 one end of the folded or cylindrical edge or back 9 of the housing is expanded as shown on an enlarged scale in Fig. 5, thus producing a cylindrical casing 12 with a lateral extension 12^a to receive the lock 11 and its radial extension 11^a. Casing 12 is further provided with a hollow circumferential enlargement 12^b, extending through approximately 90°, and serving to receive and permit movement of a radial lug or stud 13 formed upon a disk 14, which is here shown as secured by screws 15 to the inner end of a rotatable cylindrical barrel 16 of lock 11, but which may be integral with said barrel. The length of lock 11, including the disk 14, is such that when inserted into its casing 12 and pushed home, or to a position in which its outer end is flush with the end of the housing, the lock shall abut squarely against the proximate end of the pintle slide, as in Fig. 2, the slide and its pintles being at such time in link-engaging position or adjustment. The movement of the pintle slide in link-engaging direction is limited by the shank or stem of a thumb-piece 17, preferably roughened, which stem passes through a slot 18 in the housing, and is riveted or otherwise permanently attached to the slide. The movement is also restricted by the links 8.

Any suitable lock capable of insertion into the casing 12, and of locking engagement with the housing, may be employed. In practice I find a lock of the general type of the well-known Yale or Corbin locks, using a flat key, said key having one longitudinal edge provided with alternate elevations and depressions, peculiarly well adapted to the purpose, and the lock 11 shown in the drawing is of this character. As here shown the lock shell or case consists of a hollow cylinder of diameter to fit neatly and turn freely within the casing 12 of housing 4 and the radial extension 11^a, said extension fitting and filling the seat in the lateral extension 12^a of the lock casing, and preventing the lock shell from rotating in casing 12. Filling the cylindrical body of the lock shell is the rotatable barrel 16, in which is formed a narrow longitudinal keyway 20, of form and size to admit a key 21.

Opening into the keyway 20 from the circumference of the barrel 16 on that side next the case extension 11^a with the parts in the positions they occupy when the key is being inserted or withdrawn, are radial holes 22 of diameter somewhat greater than the thickness of the key, as seen in Fig. 3. Each of the holes 22 is occupied by a tumbler 23, preferably of cylindrical form, the several tumblers being of unequal lengths so that when the key is inserted its full distance

their outer ends shall be brought flush with the circumference of the barrel 16, or exactly to the meeting line of the barrel and the lock shell. The inward movement of tumblers 23 is limited and determined by the depths of the holes 22.

As seen in Figs. 2 and 3, the extension 11^a of the lock shell is provided with holes 24, which are carefully alined with the holes 22 of barrel 16 when the barrel is in key-receiving position, as shown in Figs. 2 and 3. Each hole 24 receives first a helical spring 25 and then a short rod or stem 26, similar to the tumblers 23. The springs 25 are of such length that they are put under compression when the rods 26 are inserted and pressed inward until their outer ends are flush with the inner face of the cylindrical body of the lock shell. As a consequence, the springs tend constantly to force the rods or stems 26 outward from the holes 24, and do so when the key is withdrawn and the tumblers 23 are thus made free. In so moving outward, the rods or stems 26 abutting against the tumblers 23, force them inward in their holes or seats, crossing the meeting line of the barrel 16 and lock shell 11, and entering the open ends of the holes 22 of barrel 16. In this way the barrel is securely locked against rotation or movement in any direction relatively to the lock shell.

As stated, barrel 16 of the lock has at its inner end a disk or enlargement 14 which, as shown in Figs. 2 and 5, bears against the inner end of the cylindrical lock shell, and carries on its circumference a radial lug or stud 13. This stud, when the lock is seated in the housing, is in plane with the circumferential enlargement 12^b of the lock casing 12, but in 90° relation to the plane of the keyway 20, hence when the key is withdrawn the lug or stud 13 stands within and at the closed end of the enlargement 12^b, as seen in Fig. 4, thus precluding withdrawal of the lock from the housing. When, however, the key is inserted and pressed home, thereby moving the tumblers 23 outward and forcing back the rods or pins 26, thus releasing barrel 16, the barrel can be turned by the key, and being so turned it will carry stud 13 from the position shown in Fig. 4 into alinement with the extension 12^a of lock casing 12 and out of enlargement 12^b, permitting withdrawal of the lock from the housing. This done, the pintle slide can be moved in link-releasing direction, releasing the links at one end and permitting insertion or removal of a leaf or leaves, or re-arrangement thereof, as desired, after which the links are returned to locking position, the pintle slide is moved to pintle-engaging adjustment, the lock is inserted into casing 12, the key is turned, carrying with it barrel 16 and moving lug 13 into enlargement 12^b, and the key is withdrawn, whereupon the

lock springs 25 move pins 26 outward, forcing back the tumblers 23 and locking barrel 16 against movement.

The circumferential enlargement 12^b is preferably closed or covered, and may be drawn up by dies before the blank is folded, the covering or closing of said enlargement serving to prevent access to lug 13 in attempting to force the lock. Obviously, however, a simple opening in the casing into or through which the lug may extend, would serve to receive said lug and prevent withdrawal of the lock from the casing.

While I have illustrated and described the preferred embodiment of my invention, it will of course be understood that such modifications as fall within the province of the skilled mechanic or designer may be made without departing from the scope of the invention.

What is claimed is:

1. In a loose leaf binder of the character described, a housing having a substantially cylindrical folded edge enlarged at one end to form a lock-receiving casing, the two walls of the housing inward from the folded edge being spaced a distance apart to form a guideway for a pintle slide and a lateral extension of the lock-receiving casing, said casing being further provided with a circumferential opening extending to and communicating with its lateral extension; a slide seated and longitudinally movable in said guideway and provided with pintles; leaf-carrying links having perforations to receive said pintles; and a lock having a shell of form and dimensions to enter and occupy the enlarged casing and the lateral extension thereof and provided with a rotatable barrel having a radial lug which, when in alinement with the lateral extension of the lock shell, can enter and pass through the lateral extension of the lock casing, and when the lock is fully seated in said casing may, through rotation of the barrel, be carried into the circumferential opening of the casing.

2. In a loose leaf binder of the character described, and in combination with a housing having a folded edge of cylindrical form enlarged at one end to constitute a lock-receiving casing, said casing provided with a lateral extension and with a circumferential opening; a lock having a cylindrical shell provided with a lateral extension adapted to fit and fill the lock-receiving casing, said lock being provided with a rotatable barrel having a radial projection which may be brought into alinement with the lateral extension of the lock shell to permit insertion of the lock into its casing, and which may thereafter be carried into the circumferential opening of the casing through partial rotation of the barrel.

3. In a loose leaf binder of the character described, and in combination with a hous-

ing having a folded edge of cylindrical form enlarged at one end to constitute a lock-receiving casing, said casing provided with a lateral extension and with a circumferential opening communicating therewith; a lock having a cylindrical shell provided with a lateral extension and adapted to fit and fill the lock-receiving casing, said lock being provided with a rotatable barrel having a radial projection which may be brought into alinement with the lateral extension of the lock shell to permit insertion of the lock into its casing, and which may thereafter be carried into the circumferential opening of the casing through partial rotation of the barrel; and means for locking the barrel against rotation in the shell when the key of the lock is withdrawn.

4. In a loose leaf binder of the link-and-pintle type, a housing provided with openings for the introduction of the perforate ends of leaf-carrying links; leaf-carrying links extending through said openings; a slide seated and longitudinally movable in said housing and provided with pintles to enter the eyes of the links; and a lock insertible into and removable from the end of the housing, abutting against the end of the slide when the latter is in link-engaging adjustment, and provided with means for retaining said lock in its seat in the housing when the key is withdrawn from the lock.

5. In a loose leaf binder of the link-and-pintle type, a housing provided with openings for the introduction of the perforate ends of leaf-carrying links; leaf-carrying links extending through said openings; a slide seated and longitudinally movable in said housing and provided with pintles to enter the eyes of the links; and a lock having a rotatable barrel adapted to be engaged and disengaged with and from the lock casing through partial rotation, and provided with means for locking said barrel against rotation when the key is withdrawn from the lock.

6. In a loose leaf binder of the link and pintle type, a slide housing having a folded edge of cylindrical form enlarged at one end to produce a lock-receiving casing and provided with spaced openings in the folded edge to receive one end of leaf-carrying links; links provided with eyes and extending into said openings; a slide movable longitudinally within said housing, provided with pintles to enter the eyes of said links; and a lock adapted to enter and fill the lock-receiving casing of the housing and preclude longitudinal movement of the slide, said lock comprising a lock shell provided with a radial wing movable in a guideway in the housing and serving to hold the lock shell against rotary movement, a rotatable barrel in said shell, tumblers, and spring-pressed pins, said pins arranged in seats in the lock shell and serving

- when the key is withdrawn to engage the barrel and prevent rotation thereof, said barrel being provided with a radial lug to enter a circumferential opening in the wall of the lock-receiving casing when the barrel is turned to carry said lug out of alinement with the wing of the lock shell.
6. In a loose leaf binder of the link-and-pintle type, a housing having a folded edge of cylindrical form enlarged at one end to constitute a lock-receiving casing and provided in its folded edge with openings to receive one end of leaf-carrying links; links projecting into said housing and perforated 10 to receive pintles; a pintle-bearing slide mounted and longitudinally movable in the housing; and a lock insertible into the lock-receiving casing of the housing and serving, when properly seated and secured therein, 15 to prevent longitudinal movement of the slide when the latter is in link-engaging position.
7. In a loose leaf binder of the link-and-pintle type, a housing having a folded edge of cylindrical form enlarged at one end to constitute a lock-receiving casing and provided in its folded edge with openings to receive one end of leaf-carrying links; links projecting into said housing and perforated 20 to receive pintles; a pintle-bearing slide mounted and longitudinally movable in the housing; and a lock insertible into the lock-receiving casing of the housing and serving, when properly seated and secured therein, 25 to prevent longitudinal movement of the slide when the latter is in link-engaging position.
8. In a device of the class described, a back member, a housing having an open end secured to the back member, a pintle-carrying 30 slide slidably mounted in the housing, a removable member engaging the end of the slide to restrain the latter from movement, and means on the member interlockingly engaged with the housing for locking said member in position.
9. In a device of the class described, a back member, a housing having an open end secured to the back member, a pintle-carrying slide slidably mounted in the housing, a removable member closing the open end of the housing and restraining the slide from movement, and means carried by the member adapted to be moved into engagement with the housing for locking said member in position.
- 40 10. In a loose leaf binder, a housing having an open end and provided with openings for the introduction of the perforate ends of leaf carrying links, leaf carrying links extending through said openings, a slide longitudinally movable in said housing and provided with pintles adapted to enter the perforate ends of the links, a member closing the open end of the housing to prevent movement 45 of the slide to withdraw the pintles from the links and adapted to be removed from the housing to permit movement of the pintles relative to the links, and means for locking said member in position.
- 50 55 11. In testimony whereof I have signed my name to this specification.

JOHN L. McMILLAN.
